UNITED STATES PATENT OFFICE.

FRANK MOSSBERG, OF ATTLEBORO, MASSACHUSETTS, ASSIGNOR OF ONE-THIRD TO
SAMUEL M. EINSTEIN AND ONE-THIRD TO CLARENCE L. WATSON, BOTH OF
ATTLEBORO, MASSACHUSETTS.

CARTRIDGE-CLIP.

1,292,629.

Specification of Letters Patent. Patented Jan. 28, 1919.

Application filed July 17, 1918. Serial No. 245,287.

To all whom it may concern:

Be it known that I, FRANK MOSSBERG, a citizen of the United States, residing at Attleboro, in the county of Bristol and State 5 of Massachusetts, have invented certain new and useful Improvements in Cartridge-Clips; and I do hereby declare the following to be a full, clear, and exact description of the invention, such as will enable others 10 skilled in the art to which it appertains to make and use the same.

My invention relates to cartridge clips for use in magazine guns, and contemplates more especially an improved form of spring 15 retaining means therefor.

An object of the present invention is the production of cartridge clips in which the spring member is provided with a plurality of retaining lugs upon opposite ends thereof 20 of, arranged and adapted to engage the edge of the end or outermost cartridges, and firmly hold the contents of the clip in position.

Another object of this invention is the 25 production of a clip which can be loaded and reloaded without danger of the retaining lugs breaking off and rendering the clip useless, as is now the case with the preferred type of clips in use.

A further object of the invention is the 30 production of a clip having a series of angularly disposed and oppositely positioned retaining lugs, designed to hold cartridges firmly in position within the clip, and at the 35 same time permit them to leave the clip in an easy and even manner when being fed into the gun for use.

A still further object of this invention is the 40 production of a clip made of light, strong and substantially non-yielding material, such as steel or the like, whereby its use and re-use in training camps, on proving grounds and elsewhere is rendered both economical and highly advantageous.

With these and other objects in view the 45 invention further consists in the construction and arrangement of coöperating members, hereinafter described and pointed out in the appended claims.

In the drawing which shows a few em- 50 bodiments of my invention—

Figure 1 is a view in side elevation partly in section on a slightly enlarged scale of

the preferred form of clip with the usual number of cartridges in position. 55

Fig. 2 is an inner face view of the clip showing the cartridges removed, but the position of the heads thereof indicated by a series of contacting dotted circles.

Fig. 3 is an end view the clip showing the 60 position of the oppositely arranged lugs in operative position against the cartridge.

Fig. 4 is a detached perspective view of the spring member of the clip.

Fig. 5 is an end view of a modified form 65 of clip, in which the retaining lugs are formed upon the sides of the clip holder or trough-shaped body portion at each end thereof, and

Fig. 6 is a detail sectional elevation of 70 the form shown by Fig. 5.

The present invention has been designed to overcome certain disadvantages in manufacture and use which have been found to exist in the type of clips heretofore em- 75 ployed. One of the disadvantages is due to the construction of the spring member of

the clip with bendable retaining lugs provided at each end thereof. In the matter of manufacture, it will be apparent that 80 these lugs must be bent over the end cartridges in each clip, and that such operation must be performed either manually or by a machine. In use, when these lugs have been bent back to permit release of cartridges for 85 firing, any rebending thereof for purposes of retaining another set of cartridges will result in breaking them, thereby rendering the clip useless, at least until another spring member has been supplied. It has also 90

been an objection to the manufacture of the known type referred to that a malleable material, such as brass, must be employed, which material is expensive and its relative thickness as compared with other materials 95 considerably increases the weight of the clip. The necessity for using brass or like material, especially in the spring members, as heretofore manufactured, arises from the fact that the retaining lugs have to be bent, 100 and any material other than this, or its equivalent, would not permit of such an operation.

The aforesaid disadvantages and difficulties which have heretofore attended the pro- 105 duction and use of ordinary cartridge clips

have necessitated the practical improvements herein described and illustrated in the accompanying drawing.

My improved form of clip comprises 5 among other things, a cartridge holding member of trough-shape, in which is positioned a spring member provided at each end with oppositely arranged retaining lugs. The cartridges are pressed into the holder 10 against the tension of the said spring member and are yieldingly held in place by means of the retaining lugs upon each end of the said spring member. In loading, the cartridges are pressed over the retaining 15 lugs, as will be readily understood.

Referring to the drawing in which corresponding reference characters designate similar parts in the several figures, my clip includes a holder 1 having opposite side 20 flanges or walls 2 bent in a manner to form longitudinal grooves or recesses 3 in which the heads of cartridges are slidably positioned. These grooves or recesses 3 are formed by the side walls 2 being turned back 25 upon themselves and then bent inwardly in a lateral direction across the trough or channel-way of the holder, as clearly shown in Fig. 3. The back of the holder may be slightly grooved or corrugated as shown at 30 4 for purposes of strength.

The back of the holder 1 is also provided with spaced tongues or abutments 5, which may be struck up from the material forming the back of the holder. These abutments 5 are designed to coöperate with interlocking tongues or abutments 6 formed upon the spring member 7, now to be described.

The spring member 7 is made of light and durable material, such as steel, and is 40 given the usual spring curve for exerting a gripping action upon the heads of the cartridges. Suitable guides or tracks 8 are formed upon opposite sides of the surface of the spring member, and these tracks 8 45 terminate short of the ends of the spring aforesaid thus serving to guide the cartridges in a free and easy manner, as will be readily understood. At the ends of the tracks and slightly spaced therefrom are retaining lugs 9 arranged in an angular position with relation to the aforesaid tracks, and preferably formed upon a sector of an arc struck from a radius corresponding with that of the head of the cartridge. Two lugs 50 55 are provided upon each end of the spring member, as best shown by Fig. 4, and while I have shown lugs 9 of arcuate form, I do not so limit them, it being understood that slight changes in their form and shape may be resorted to without departing from the invention set forth.

The lugs 9 are oppositely disposed for the purpose of uniformly retarding and retaining the cartridges, and at the same time to 60 65 permit their even discharge from the clip

into the gun for firing. The lugs are preferably rounded upon their upper surfaces to permit of cartridge heads being the more readily drawn over them, and their angular arrangement also materially assists in the 70 regular and even passage from the clip.

In assembling the component parts of the improved clip, the spring member 7 is pressed into the grooves or recesses 3, until tongues 6 carried by the member 7 spring 75 behind and against the abutments or tongues 5 formed on the holder 1, see Fig. 1. The loaded cartridges are now forced into the clip, the heads thereof sliding within the recesses 3 on the guides or tracks 8, and beneath the inwardly bent portions of side walls 2, hereinbefore described. As shown, five of these cartridges are positioned in the clip, the heads thereof abutting as shown in full lines by Fig. 1, and by dotted lines in 80 Fig. 2.

The end cartridges find bearings against the oppositely arranged retaining lugs 9 as clearly shown by Fig. 2. By this construction and arrangement also it will be seen that the cartridges are uniformly retained within the holder. It will also be apparent that their discharge from the clip into the gun for firing will be even, as the cartridge passes over the lugs into the firing chamber 95 of the gun in the usual manner.

In operation, the tension of the spring member 7 is overcome by action of the cartridge heads in riding over the retaining lugs 9, as will be readily understood, suitable clearance being provided to permit of the operation and action of the spring member 7.

In the form of clip shown by Figs. 5 and 6, the retaining means 9^a is formed upon the ends of the inwardly bent portions of side walls 2, and consists of slightly depressed ends, the purpose of which is to engage the heads of the end cartridges to retain them in position. As a cartridge is withdrawn from the clip the end of the spring member 7 yields slightly, thereby allowing its ready release. There are four of these lugs 9^a which serve to uniformly retain the cartridges and at the same time when in use on a gun, permit of the cartridges being easily and uniformly withdrawn.

From the foregoing it will be obvious that I have produced a clip in which the simplicity of construction makes it possible to 120 use and reuse the same indefinitely, an advantage which is of very great importance, particularly at the present time from a military and economic point of view, in the large training camps and proving grounds throughout the country, the reduced cost of production also being a material factor.

I am aware that numerous attempts have been made to apply stops upon clips for purposes of holding and retaining the car- 130

tridges, but all of these have proven disadvantageous because of the unevenness of retention, and the tendency to unduly retard the passage of cartridges from the clip due 5 to the location and form of these stops.

Having thus described my invention, what I now claim is:

1. A clip for cartridges comprising a holding member provided with side flanges 10 having recesses therein, a spring arranged in said holding member for positioning cartridges therein, and a series of lugs formed upon each end of said spring for engaging the cartridges and retaining them within 15 the aforesaid recesses.

2. A clip for cartridges comprising a holding member, and a spring arranged in said holding member for positioning cartridges therein, said spring being provided 20 at each end with oppositely disposed lugs adapted to engage the end cartridges and retain the contents of the clip within the holding member.

3. A clip for cartridges comprising a 25 holding member, and a spring arranged in said holding member for positioning cartridges therein, said spring being provided at each end with angularly disposed and oppositely arranged lugs adapted to engage the 30 end cartridges to retain the contents of the clip within the holding member.

4. A clip for cartridges comprising a holding member, and a spring arranged in said holding member for positioning cartridges therein, said spring being provided 35 at each end with arcuately arranged lugs adapted to engage the circumferential heads of the end cartridges and to retain the contents of the clip within the holding member.

5. As an article of manufacture, a spring 40 for cartridge clips having a plurality of oppositely arranged lugs at each end thereof.

6. As an article of manufacture a spring 45 for cartridge clips having a series of angularly disposed lugs at each end thereof.

7. As an article of manufacture a spring for cartridge clips having a series of lugs arranged at each end thereof and having their upper surfaces slightly rounded.

8. As an article of manufacture, a spring 50 for cartridge clips having spaced guides terminating short of the ends of said spring, and a plurality of lugs between the end of the spring and the terminal ends of said 55 guides.

In testimony whereof I affix my signature, in presence of two subscribing witnesses.

FRANK MOSSBERG.
